UNITED STATES PATENT OFFICE.

NORMAN V. DUDLEY, OF SEATTLE, WASHINGTON.

SUPPORT FOR CLOTHES-LINES AND HAMMOCKS.

1,159,192.

Specification of Letters Patent.

Patented Nov. 2, 1915.

Application filed February 27, 1915. Serial No. 10,980.

To all whom it may concern:

Be it known that I, NORMAN V. DUDLEY, a citizen of the United States, residing at Seattle, in the county of King and State of Washington, have invented certain new and useful Improvements in Supports for Clothes-Lines and Hammocks; and I do hereby declare the following to be a full, clear, and exact description of the invention, such as will enable others skilled in the art to which it appertains to make and use the same.

This invention relates to a combined clothes line and hammock support, and the primary object is to provide a support which may be quickly and easily put up or taken down when desired.

Another object of this invention is to provide a support wherein a pair of bars are hingedly connected for positioning at acute angles to each other for forming supporting legs, and to construct hooks upon both ends of the hinge pins which are adapted for supporting a hammock, or clothes line attaching bars, and a bracing rod or member.

A still further object of this invention is to provide a pair of bars having a plurality of eyes secured to opposite faces thereof, which are provided for supporting a clothes line and are attachable to one of the hooks formed upon one end of the hinge pin.

With the foregoing and other objects in view this invention consists in such novel features of construction, combination and arrangement of parts as will be hereinafter more fully described, illustrated in the accompanying drawings and claimed.

In describing the invention in detail reference will be had to the accompanying drawings wherein like characters designate like or corresponding parts throughout the several views, and in which:

Figure 1 is a side elevation of the improved support showing a hammock suspended therebetween. Fig. 2 is a top plan view of the improved support showing a clothes line supported thereby. Fig. 3 is an end view of Fig. 2, and Fig. 4 is a detail perspective view of the hinge used for connecting the inclined supporting leg of the support.

Referring more particularly to the drawings, 1 and 2 designate standards of the supporting structure, which are formed of a pair of bars 3 and 4 which are hingedly connected at their upper ends as is clearly shown at 5 in Figs. 2 and 3 of the drawings.

The hinges 6 which are used for hingedly connecting the bars 3 and 4 have leaves 7 and 8 which are constructed in the ordinary manner having interlocking sleeves 9 formed upon their meeting ends through which sleeve is inserted a pin 10. The hinge pin 10 has hooks 11 and 12 formed upon its ends, by the curving of the pin to assume a hook shape. The hook 11 is of smaller size than the hook 12 and is positioned outwardly from the edges of the bars 3 and 4.

The hooks 11 have secured thereto stay or bracing members 13, which may be either chains or rods, as shown in Figs. 1 and 2. The bracing or stay members 13 have pins 14 secured to their lower ends, which pins are adapted for insertion into pipe guide-ways 15 which are driven angularly into the ground as is clearly shown in Fig. 1 of the drawings. The pins 14 and the stay or bracing members 13 securely brace and hold the standards 1 and 2 in vertical position.

The hooks 12 which are positioned inwardly of the facing sides of the standards 1 and 2 are shown connected in Fig. 1 by a flexible member 16 which further aid the bracing or stay members 13 in holding the standards in rigid vertical position. The flexible member 16 is used only when the device is utilized for supporting a hammock.

In Fig. 1 of the drawings, the hooks 12 are shown as having suspended therefrom and between the standards 1 and 2 a hammock 17. The hammock 17 is connected to the hook 12 by the ordinary type of hammock suspending rope 18.

In Figs. 2 and 3 of the drawings the hooks 12 have connected thereto bars 20. The bars 20 are loosely connected to the hooks 12 by eye bolts 21 which are secured to the side edges of the bars. The bars 20 have secured to the side edges to which the eye bolts 21 are secured eye bolts 22, to which are swivelly connected hooks 23. The hooks 23 are provided for having their hook ends 24 inserted through eyelets 25 which are carried by the side edges of the bars 2 and 3, for holding the bar 20 securely in a horizontal position. The hooks 23 cross each other and are connected to the bar 3 or 4 which is upon the opposite side of the hook 12 from the eye 22 to which the respective hook 23 is connected.

The bars 20 have secured to their side edge opposite to the one which carries the eye

bolts 21, a plurality of eye bolts 27 which are secured to the bars 20 in alining pairs. The eyes 27 are provided for supporting a clothes line indicated at 28. The clothes line 28 is secured to one of the eyes 27 which is carried by one of the bars 20 and passes from the bar 20 across to the other bar 20 and transversely thereto through another eye 27 and back to the original bar 20, and so on until the clothes line has been threaded through all of the eyes 27 and secured to the last eye for securely supporting the clothes line between the upright braces 1 and 2.

In reducing the invention to practice certain minor features of construction, combination and arrangement of parts may necessitate alterations to which the patentee is entitled provided such alterations are comprehended within the scope of what is claimed.

What is claimed is:—

1. In a device as set forth, a pair of vertical uprights each comprising a pair of bars, hinge leaves secured to the inner sides of the upper ends of said bars, a hinge pin connecting said hinge leaves and extending

beyond the edges of said hinge leaves, said pin having its ends curved for forming supporting hooks.

2. In a device as set forth, a pair of vertical standards disposed in spaced relation to each other, each of said standards comprising a pair of bars, hinge leaves secured to the upper ends of said bars, a hinge pin connecting said hinge leaves, said hinge pin projecting beyond the side edges of said hinge leaves and having its ends curved to form supporting hooks which extend outwardly from the outer and inner sides of said side edges of said bars, stay members secured to the outwardly extending hinge pin supporting hook, pins for detachably securing said stay members to the ground, said inwardly extending hinge pin hooks being provided for supporting the article to be supported between said standards.

In testimony whereof I affix my signature in presence of two witnesses.

NORMAN V. DUDLEY.
